UNITED STATES PATENT OFFICE.

ROBERT CRAWFORD JOHNSON, OF LEICESTER, ENGLAND, ASSIGNOR TO CUBE TEAPOTS
LIMITED, OF LEICESTER, ENGLAND.

DESIGN FOR A CUP.

Application filed January 9, 1926. Serial No. 16,014. Term of patent 14 years.

To all whom it may concern:

Be it known that I, ROBERT CRAWFORD JOHNSON, a subject of the King of Great Britain, residing at Roxton, Springfield Road, Leicester, England, have invented a new, original, and ornamental Design for a Cup, of which the following is a specification, reference being had to the accompanying drawing, forming part thereof.

The figure is a perspective view of a cup showing my new design.

I claim:—

The ornamental design for a cup as shown.
In witness whereof I have signed this specification.

ROBERT CRAWFORD JOHNSON.
